LIGHTER FOR ORCHARD HEATERS

Walter A. Lea, Los Angeles, and Earl Vincent Ehrhardt, Altadena, Calif.

Original application November 26, 1937, Serial No. 176,614. Divided and this application May 4, 1942, Serial No. 441,746

1 Claim. (Cl. 158—42.1)

This application is a divisional application of what has been shown, claimed and allowed in a former application of ours for an Orchard heater, filed November 26, 1937, Serial No. 176,614, now Patent No. 2,286,366, issued June 16, 1942.

This invention, as shown and claimed herein, relates to lighters for the burners of orchard heaters, which burners are adapted to burn gaseous or liquid fuels for heating the air in large open areas, principally and primarily for orchards where a plurality of burner equipped heaters are used to warm the outside air in defense from frost. Our lighters may be used also with burners in large areas to be heated in approximately the same manner as in an orchard area.

The service required for this type of heating requires a great many heaters as a general installation. The time element for lighting these heaters is sometimes such that a single person must start in operation a good many heaters in a relatively short space of time on occasion of sudden changes in atmospheric temperatures.

When liquid or gaseous fuels are used for the burners it is desirable to provide central storage volume supply and this connected by suitable piping to separate burners, yet single tanks may be used at each heater if desired.

The burners for which our lighters are normally to be used will burn liquid or gaseous fuel supplied by any suitable piping means.

An object of the invention is to provide a special igniting means which will automatically light the burner when a valve is opened allowing a fuel supply to enter the burner.

A further object of the invention is to provide a lighting means for the fuel in the burner which will automatically light a pilot flame from a fuel supply from a special conductor and at the same time open up a conductor to the main fuel line conductor for the regular supply for the main fuel burner.

Another object of the invention is to provide an automatic lighter for a pilot light having a special fuel supply for lighting and a fuel supply for the burner and automatic means for igniting the pilot burner and for shutting off the supply of fuel to the pilot burner as and when the fuel burner is supplied from the general supply of fuel.

Our invention is incorporated with an orchard heater to such an extent that we will describe the heater in general terms and specifically as to the mechanisms in which our lighter is associated with the orchard heater for a better understanding of the operation of our lighter.

Reference will be had to the accompanying drawings in which

Fig. 1 is a view in side elevation of the heater with a part of the flue taken away.

Fig. 2 is a sectional elevation of two associated fuel supply tanks and tank heaters.

Fig. 3 is a schematic plan view of an orchard showing one possible arrangement of heaters therein.

Fig. 4 is an enlarged elevational view of the heater shown in Fig. 1, with the pilot hood shown in section.

Fig. 5 is a side elevational view in section of the burner end of the heater taken along the line 5—5 of Fig. 4, the pilot assembly being shown in side elevation in front of the section plane.

Fig. 6 is a vertical sectional view of the pilot assembly taken along the line 6—6 of Fig. 5.

The orchard heater shown in the drawings in which our lighter is assembled and which is described herein as a lighter for the burner of a heater, is provided with a perforated, horizontally disposed heater flue 11 of any suitable construction and shape. Thus flue 11 is supported at its outer end by any suitable standard 16 above the ground 17.

At the front end of the flue 11 there is an end wall 22 secured to the body of the flue 11 in any suitable manner.

Into this end wall 22 of the flue 11 there is secured by screws 18 a burner casting 19 having a hollow mixing cylinder 25 and a goose neck projection 26 entering rearwardly from the under side of cylinder 25. The whole of which mechanism is supported upon a vertical standard 20 mounted on a pedestal or base 21 resting on the ground 17.

A cylindrical hood 98 having a ring of louver openings 99 and a top portion 100, covers the burner and lighter mechanisms from the outside weather contact.

The fuel for the burner comes to the heater by means of a pipe 52, see Fig. 1, from any suitable supply tanks 101 and 102, see Fig. 2, in which is shown a liquid fuel 112 of any suitable quality.

Those tanks 101 and 102 are duplicates for the purpose that when one becomes empty the other tank will be used for fuel supply while a refill takes place in the other tank.

A pressure of air or gas is carried in the tanks for the purpose of furnishing a more or less constant pressure of fuel in the supply pipe 52 of sub-stations or single heaters.

The pipe 52, or duplicates thereof in other heaters, are supplied with fuel from the storage tanks 101 and 102 by pipes 107 and 108, see Fig. 2.

Fig. 3 indicates a plan of an orchard arrangement of the trees and the locations of the heaters 109 and 110 the fuel for which is supplied by pipes 107 and 108.

The arrangements of the piping at the discharge locations from the tanks are shown in Fig. 2 of the drawings, but are not described herein in detail as they are not necessarily a part of this invention save only as to indicate the fuel supply conditions under which our invention operates. The front of the heater and all the mechanisms of the burner and the lighter are connected to be supported by and from the standard 20 having its lower end 31 fixed into the base or pedestal 21. This standard 20 may be a solid bar or a tube in which the top end must be covered.

At the upper end of the standard 20 there is mounted a T pipe fitting 32 and in the top of this fitting 32 there is a pipe section 33.

The top of the pipe 33 is screwed into a boss 34 of the burner casting 19 whereby the burner and the front end of the flue 11 are supported from the pedestal base 21.

Into the side opening S of the T fitting 32 there is mounted an elbow fitting 55, see Figs. 5 and 6, in which there is screwed a horizontal nipple 56. The right end of this nipple 56 is enlarged and this end is screwed into the side wall of a band 46. This band 46 is located about midway of and embraces a cylinder 44. This nipple 56 is terminated into a small nose projection at its right end which enters into the left wall of the cylinder 44. A passageway 57 of the nipple 56 enters into the cylinder 44 at the port location 62, see Fig. 6.

Thus there is a passageway from the interior of cylinder 44 at approximately its midway length which passes from the cylinder through the nipple 56, the fitting 55 and the pipe 33, and this is the passageway through which the fuel supply for the burner is conducted to a burner tip or nozzle 39.

The entire fuel supply for the heater of this unit comes through the pipe 52 into a T fitting 50 which is screwed into the base plug 48 in the lower end of the cylinder 44 and through the port opening 49 in the plug 48.

The T fitting 50 is connected to the pipe 52 by a compression joint 90 which holds the end of the pipe 52 in communication with an opening 51 of the T shaped fitting 50 in which opening 51 there is the valve seat 53 adapted to be opened and closed by a needle valve stem 54 by means of which a passageway is opened or closed for fuel between the pipe 52, the passageway 51a entering into the opening port 49 of the plug 48 in the bottom of the cylinder 44 into which all the fuel which enters into the burner must enter and pass.

The top of the cylinder 44 is closed by a cylinder head 47 and in this head 47 there is a passageway port 63 which opens into a nipple 65 of the pipe fitting 66 in which there is fixed a pilot tubing 64 which conducts fuel to a pilot burner. The upper end of the pilot tubing 64 is provided with a mixing cup 70 screwed on at 71 to the top end of pipe 64 and the bottom of this cup 70 is provided with air passageway 71a. Thus when fuel comes through the pipe 64 from the upper section 58b of the inside 58 of the cylinder 44, there will be discharged outwardly out of the cup 70 a combustible material which when ignited will become an igniting pilot flame for the fuel

discharged by the aforementioned nozzle 39 of the burner.

In the cylinder 44 there is a piston block 59 on the top of which is mounted a synthetic rubber 5 or any suitable valve disk 67 fixed to the upper face of the said piston block 59. On the cylinder head 47 there is a valve seat 68 on an angular projection 69 of the cylinder head 47.

The piston 59 on its left side wall is provided 10 with a small groove 59a, see Fig. 6, the purpose of which is to allow a seepage of fuel to pass by the piston 59 as and when the piston is lifted by the entrance of fuel coming into the cylinder 44 through the passageway port 49 through the plug 48 as and when the pressure of fuel supply is 15 opened up to enter the cylinder 44 by the opening of the valve stem 54.

The fuel supply is always under a pressure sufficient to lift the piston 59 upwardly in the cylinder 44 and carry the said piston 59 up to contact 20 with the valve seat 68 of the cylinder head 47. This leakage through groove 59a in the piston 59 allows sufficient fuel to pass above the piston 59 as the piston rises under the pressure of the entering fuel to furnish a supply for the fuel to start and keep burning the pilot flame issuing from the cup 70 to become a pilot light as and when ignited to keep this pilot light burning until the piston 59 moves the valve disk 67 to contact the valve seat 68 of the cylinder head 47, whereupon the fuel supply for the pilot light is 25 shut off. Meantime as the piston 59 passes the opening port 62 of the passageway 57 in the nipple 56, then there is opened a direct passageway 30 for fuel to pass through from the interior of the cylinder 44 to the inside of the pipe 33 whereby fuel then may enter and pass directly to the burner nozzle 39.

A piston rod 60 which is connected at 60a to the piston 59 passes through a packing 61 in the top cylinder head 47 and is connected to an arm 87 through the medium of which the ignition mechanism for the pilot flame in the cup 70 is actuated to light the pilot burner as and during 40 the time the piston 59 passes upwardly to cause valve disk 67 to contact the valve seat 68 of the cylinder head 47. The ignition mechanisms 45, hereinafter described, thus actuated by the movement of the piston 59 will have started and 45 have kept burning the pilot flame as and when fuel will pass through the pipe 33 sufficiently and will issue from the nozzle 39 to be ignited by the pilot flame before the fuel supply for said flame has been shut off by the valve disk 67 and seat 55 68 above described.

The fuel as it rises up inside the pipe 33 coming through the cylinder 44 under pressure from the supply tanks 101 and 102, as previously described, enters the opening 35 in boss 34 of casting 19 and 60 enters to a chamber 49 into a pipe heater 41 closed by a cap 42.

This heater pipe 41 is secured in horizontal position by being fastened into casting 19 and extends into the heated space in the heater flue 11. 65 An opened ended pipe 43 is located inside pipe 41 having its right end open to the space 40 in pipe 41. The other or left end of pipe 43 is screwed into the casting 19, and at this end the pipe 43 opens to a chamber 36 in the goose neck projection 26 of casting 19. The left end of projection 70 26 rises into a leg 37 having a horizontal portion 38 into which there is screwed the burner nozzle 39.

The goose neck projection 26 of casting 19 75 passes around the vertical center of nozzle 39 in

which center there is entered the ignition mechanism 45. The top of this ignition mechanism 45 is a part of Fig. 6.

Thus the chamber 36 extends around this opening in which the ignition of the fuel takes place.

The fuel heated by the heater pipe 41 which is heated by the heat of the interior of flue 11 escapes out of the nozzle 39 and siphons in the outside air around the nozzle and enters into the horizontally disposed cylinder hood 27 fixed at 28 into the casting 19. From this hood 27 the burning fuel passes into a horizontal mixing chamber 25 the nozzle of which is indicated by 30.

The ignition of the fuel from the pilot cup 70 together with the fuel from the nozzle 39 takes place by the lighting means broadly indicated by 45. This lighting means will now be described.

The frame for the ignition mechanism 45 is a channel shaped upright 72 which is mounted in position by means of a nut 73 threaded upon the nipple 56, by which it is drawn into a fixed position against the band 46.

A pin 74 is revolvably mounted between flanges 75 and 75' of the upright 72. These flanges extend upwardly a short distance above the upper end of channel web 76. The pin 74 projects beyond the flange 75' and has fixedly mounted upon the projecting portion a steel disk 77, the rim of which is serrated and frictionally contacts a piece of flint 78. This flint is held resiliently against the rim of the disk 77 by means of a spring (not shown) within a housing 79 mounted on the outer face of the channel flange 75'.

The peripheral rim of the disk 77 and the flint 78 are so constructed and their contact relationship is of such a character that when the disk 77 is given a rapid movement of rotation through a small arc, sparks are generated sufficient to ignite the jet of fuel gas or liquid fuel issuing from the adjacent pilot cup 70. This rapid rotational movement is imparted to the disk 77 by means of mechanism described as follows.

An impulse wheel 80 is loosely mounted upon the pin 74 between the channel flanges 75 and 75'. The pin 74 is formed with an axial projection 81 extending toward the channel flange 75', having jaws 82 which engage in mating relationship to jaws 83 formed on a disk 84 which is keyed or otherwise fixedly secured to the pin 74. The impulse wheel 80 is resiliently held axially against the disk 84 by means of spiral spring 85 interposed between the flange 75 and impulse wheel 80. The impulse wheel 80 is provided with an integral dog 86 which is resiliently held in a vertically dependent position against the upper end of an arm 87 by means of a spring 88 secured at its upper end to the dog 86 and at its lower end to the flange 75. The arm 87 is channel shaped in cross section and is arranged with its flanges 89 extending toward the upright 72. A block 91 is rigidly secured between the flanges

89 and the arm 87 and is formed with an upwardly extending lip 92 which mates with a notch 93 formed on the lower end of dog 86. The arm 87 is hinged at its lower end to the upper end of the piston rod 60 and at its upper end its web 84 engages in vertically slideable contacting relationship the outer face of the dog 86, and is resiliently held in such relationship by means of a spring 95 secured at its lower end to the outer face of the web 76 of the channel standard 72, and at its upper end to a cross arm 96 which is integrally formed upon and projects from the arm 87 near its lower end, and which extends through, and is free to move vertically in a slot 97 formed in the standard web 76.

The igniter mechanism is so constructed and arranged that when the piston 59 in the cylinder 44 is at its lowermost position, the block 91 and the dog 86 are slightly separated, and the upper end of the web 94 rests upon the back of the dog. As the piston moves upwardly, the block 91 engages the dog 86 and rotates the wheel 80, as shown in dotted lines of Fig. 6, the dog 86 disengages the lip 92 and the impulse wheel 80 is given a sudden rotation movement by the spring 88. The jaws 82 which latch idly by jaws 83 during the upper movement of the dog 86, engage these jaws 83 on the downward impulse, and the steel disk 77 rubs against the flint 78 and generates igniting sparks.

An electrical make and break sparking mechanism for ignition purposes may be substituted for the flint sparks using the impulse wheel 80 as a make and break electrical connection.

A cylindrical hood 98 formed with a ring of louver openings 99 and supported loosely on the elbow 55 serves to enclose all parts of the pilot assembly 45, protecting it from rain when the heater is used in exposed locations and shielding the pilot flame from wind. An upper horizontal portion 100 of the hood 98 serves to direct the pilot flame toward the fuel jet of the main burner and insures a quick positive ignition thereof.

We have followed in this application the structures described and shown, but not claimed in the application first above mentioned.

What we claim is:

In a heater: a fluid fuel burner; a pilot burner; a fuel supply conductor; a cylinder having at one end a fuel intake port communicating with said supply conductor, at a midway point a fuel outlet port communicating with said fuel burner, and at its other end a fuel outlet port communicating with said pilot burner; a reciprocating piston in said cylinder adapted to afford fluid passage longitudinally thereof at all positions and adapted in its movement to successively open said fuel outlet port to said fuel burner, and close said fuel outlet port to said pilot burner.

WALTER A. LEA.
EARL VINCENT EHRHARDT.
